C. E. GERBERICH

DOOR HANDLE

Filed May 21, 1924

UNITED STATES PATENT OFFICE.

CLARENCE E. GERBERICH, OF AURORA, ILLINOIS, ASSIGNOR TO LYON METALLIC MANUFACTURING COMPANY, OF AURORA, ILLINOIS, A CORPORATION OF ILLINOIS.

DOOR HANDLE.

Application filed May 21, 1924. Serial No. 714,775.

To all whom it may concern:

Be it known that I, CLARENCE E. GERBERICH, a citizen of the United States, residing at Aurora, in the county of Kane and 5 State of Illinois, have invented a certain new and useful Improvement in Door Handles, of which the following is a specification.

My invention relates to handles for locker doors and the like, and the object is to provide means by which the grip—that is, the part grasped by the operator—may be easily, securely and at the same time detachably fastened to the rock shaft which operates the door latch.

I obtain my object by the mechanism illustrated in the accompanying drawings, in which—

Figure 1 is an assembly view showing my 20 device mounted upon a locker door.

Figure 2 is similar to Figure 1 but shows the grip and a portion of the shaft in section to reveal the internal construction.

Figure 3 is a distributive view similar 25 to Figure 2 but showing the parts separated.

Like numerals denote like parts throughout the several views.

In the form selected to illustrate the principle of the invention the rock shaft 1 has a 30 reduced portion 2 forming a shank to pass through a suitable aperture in the door 4. The inner end 5 of the shank is squared to enable it to rotate the latch-operating element 6 shown in cross section in Figure 1 and typifying any form of latching or latch-operating element. This element 6 in practice is fastened to the shank, and thus constitutes a keeper to hold the rock shaft journaled in the door.

40 Near the outer end the rock shaft has a lateral recess 7 which is conically tapered. At the bottom of this recess and coaxial with it is an internally threaded recess 8 for taking the threaded portion of a cap screw 10 presently to be described. As shown, the center line or axis of the recesses 7 and 8 is radial to the shaft.

The grip 12, which the operator grasps 50 when he wishes to manipulate the latch, is tapered at the inner end to fit wedgingly into the recess 7 in the rock shaft. By preference not only is the inner end tapered but the entire grip is tapered with a bead-

ing 14 at the outer end. Thus the grip presents a symmetrical appearance and the manufacture is somewhat simplified.

The grip is hollow, thus not only reducing its weight to a minimum, but causing it to form a housing for completely enclosing and protecting the head of the cap screw 10.

The grip is held securely to the handle by the head 15 of the screw 10, and by preference this head is conically tapered to fit the interior surface of the grip.

In assembling, the inner end of the grip 12 is first inserted into the recess 7, after which the screw is inserted and screwed into the threaded recess 8. When screwed up fairly tight a wedging action will result which produces a very firm assembly and also is very effective in preventing the screw from coming loose accidentally.

It will be evident that this produces a very light and simple construction, and yet one that is extremely effective. As the head 75 of the screw is completely housed within the grip there is no danger that it will be struck from the side or suffer any similar tendency to loosen it. Furthermore as a result of the wedging action the screw will 80 be much more effectively held than if the ordinary shoulder contact were relied upon.

Having thus described my invention, what I claim as new and desire to secure by Letters Patent is:

1. A door handle having a rotatable shaft having a rigid socket at the side, a grip extending at its inner end into said socket, one of the parts being tapered to produce a wedging fit, and means for drawing the grip 90 radially toward the shaft for holding the parts rigidly assembled.

2. A handle for locker doors and the like having a rotatable shaft for operating the door latching mechanism, a grip for rotating it, said shaft and grip having a tapered interfitting connection, and means for drawing the grip toward the shaft for increasing the wedging action of said tapered interfitting connection, said grip being hollow 100 and said drawing means being completely housed within it.

3. A handle for locker doors and the like having a rotatable shaft for operating the door latching mechanism, said shaft having a tapered recess, a grip seating in said 105

recess, and means for drawing said grip into said recess for wedgingly holding the parts assembled.

4. A door handle having a rotatable shaft 5 adapted to be journaled in the door, said shaft having a conically tapered socket formed in its sides, a recess at the bottom of said socket arranged coaxially with it and internally threaded, a hollow conical grip 10 fitting into said socket, and a screw having a head adapted to engage the inner surface of the grip and having a threaded shank for screwing into said threaded recess for wedgingly holding the grip in the shaft.
- 15 5. A door handle having a rotatable shaft adapted to be journaled in the door, said

shaft having a conically tapered socket formed in its side, a recess at the bottom of said socket arranged coaxially with it and internally threaded, a hollow conical grip 20 fitting into said socket, and a screw having a head adapted to engage the inner surface of the grip and having a threaded shank for screwing into said threaded recess for wedgingly holding the grip in the shaft, 25 the grip extending outward to a substantial distance beyond the head of the screw to form a housing for the screw.

In witness whereof, I have hereunto subscribed my name.

CLARENCE E. GERBERICH.
